INVENTOR:
LEO GOLDHAMMER,

By Philip S. Hopkins,
Attorney.

UNITED STATES PATENT OFFICE

LEO GOLDHAMMER, OF MUNICH, GERMANY, ASSIGNOR TO AGFA ANSCO CORPORATION, OF BINGHAMTON, NEW YORK, A CORPORATION OF NEW YORK

DRIVING MECHANISM IN CINEMATOGRAPH APPARATUS

Application filed December 21, 1928, Serial No. 327,710, and in Germany January 11, 1928.

My present invention relates to cinematographic apparatus in which a film band is caused to travel between a windowed member and a gate which can be opened and closed by movement relatively to the window; more particularly it relates to a specific structure in the feeding mechanism for motion picture film apparatus in which a claw, engaging and advancing a film strip, is so mounted 10 that the operation of opening the gate moves the claw into an inoperative position and vice versa.

A further object of the invention consists in mounting the claw in the mechanism in 15 such a manner that it can readily be removed.

In cinematograph apparatus it is necessary that the claw which is operated by the clockwork or other motor for feeding the film by engagement in the perforations of the film, 20 should be put out of operation when the gate serving as a guide for the film strip is opened.

The claw, according to the invention, has a pin and slot connection with a lever which is held by a spring against the gate. When 25 the gate is closed the claw, driven as usual on an eccentric axis on a wheel or disc of the motor, is in feeding engagement with the perforations in the film. When the gate is opened the lever is turned against the action 30 of the spring and owing to its pin and slot connection with the claw, the latter is turned on the eccentric axis, so that, although continuing to be driven, it cannot engage the film. 35

In the following detailed description of a typical form of the invention reference is had to the accompanying drawing in which

Fig. 1 is an elevation showing part of one 40 of the plates that carry the clockwork motor, to which plate the film window and gate are fixed, the gate being shown in closed position,

Fig. 2 is a like view, in which the film gate is shown open and the claw out of action,

Fig. 3 is a plan of Fig. 1.

Referring to Fig. 1 a film guide through which a film strip is to be advanced is formed by the film gate 1 and the windowed member 11.

The film gate 1 can turn on the bolt 2 and

is kept in closed position by the spring pin 3. The lever 4 is mounted to turn on pivot 5; it has a bent projection 6, which is pressed against the gate 1 by action of the spring 8 on the pin 7 carried by the lever. The claw 55 9 carries a pin 12 which enters an eccentric hole in the flywheel 14, and also a pin 13 which engages in a slot 15 in the lever 4. When the gate is opened (see Fig. 2) the claw 9 is turned on the axis of pin 12 by the action 60 of lever 4, so that it can no longer engage the film 10, which can then be moved from the windowed member 11. The claw 9 is inserted in the mechanism with its pins 12 and 13 free in the eccentric hole 14 and slot 15 65 respectively, and is held in place by a plate 17 fixed, at a certain distance, to the plate 16 that carries the clockwork motor.

I claim:

1. In a driving mechanism or cinematographic apparatus a structure constituting a guideway for a film band including a windowed member and a gate, mechanisms comprising a film engaging member having in its operative position a normal path of movement traversing said guideway for engaging and advancing a film band there-through, said film-engaging member being operatively connected to the film gate, so that opening of the gate moves the film-engaging member 70 away from the film.

2. In a driving mechanism for cinematographic apparatus a structure constituting a guideway for a film band including a windowed member and a gate, mechanisms comprising a film engaging member having in its operative position a normal path of movement traversing said guideway for engaging and advancing a film band there-through, said film-engaging member being operatively connected to the film gate, so that opening of the gate moves the film-engaging member 75 away from the film and a shutting movement removes the engaging member into its operative position.

3. In a driving mechanism for cinematographic apparatus a structure constituting a guideway for a film band including a windowed member and a gate, mechanisms comprising a film engaging member having in its 80 85 90 95 100

operative position a normal path of movement traversing said guideway for engaging and advancing a film band there-through, said film engaging member being movable out 5 of its normal path of movement, and a lever actuated by the opening movement of the gate consisting of one single piece to move said film engaging member out of its normal path of movement.

10 4. In a driving mechanism for cinematographic apparatus a structure constituting a guideway for a film band including a windowed member and a gate, mechanisms comprising a film engaging member having in its 15 operative position a normal path of movement traversing said guideway for engaging and advancing a film band there-through, said film engaging member being movable out of its normal path of movement and removable 20 into the latter, and a lever actuated by the opening and the closing movement of the gate consisting of one single piece to move and to remove said film engaging member out of and back to its normal path of movement.

25 5. In a driving mechanism for cinematographic apparatus a structure constituting a guideway for a film band including a windowed member and a gate, mechanisms having 30 a cycle of movements and including a claw member having in its operative position a normal path of movement traversing said guideway for engaging and advancing a film band there-through, said film-engaging member being operatively connected to the film 35 gate, so that opening of the gate moves the claws away from the film.

40 6. In a driving mechanism for cinematographic apparatus a structure constituting a guideway for a film band including a windowed member and a gate, mechanisms having 45 a cycle of movements and including a claw member having in its operative position a normal path of movement traversing said guideway for engaging and advancing a film band there-through, and a lever device operatively connected with the film gate and the claw member, so that opening of the gate moves the claws away from the film.

50 7. In a driving mechanism for cinematographic apparatus a structure constituting a guideway for a film band including a windowed member and a gate, mechanisms having 55 a cycle of movements and including a claw member having in its operative position a normal path of movement traversing said guideway for engaging and advancing a film band there-through, and a lever connected with the claw member in slot and pin connection and provided with a nose which is actuated by the gate upon an opening movement of the latter.

60 8. In a driving mechanism for cinematographic apparatus a structure according to 65 claim 6 in which the claw member is remov-

ably mounted on an eccentric axis of the flywheel of the motor and held in operative position by a cover plate.

In testimony whereof, I affix my signature.

LEO GOLDHAMMER.
